UNITED STATES PATENT OFFICE

2,052,975

HAMMER

Charles L. Griffin, Birmingham, Ala.

Application May 24, 1935, Serial No. 23,284

2 Claims. (Cl. 153—32)

My invention relates to hammers and more particularly to the type adapted to impart several hundred blows per minute in working sheet metal into various shapes, such as in removing dents from automobile bodies and fenders, and contemplates the provision of a device in which the several parts are so arranged and proportioned as to form a very effective, compact, and exceedingly small hammer which can be readily used with one hand.

My invention further contemplates the provision of a device of this kind provided with a light weight plunger and a relatively heavy housing and, by so proportioning the weights of these parts, it has been possible to practically eliminate the transmission of shocks and vibration to the arms of the operator.

My invention embodies other novel features, details of construction, and arrangement of parts which are shown in the drawing and hereinafter set forth in the specification and claims.

Apparatus embodying features of my invention is illustrated in the accompanying drawing, forming part of this application, in which:

Fig. 1 is a front view of my improved hammer;

Fig. 2 is a sectional view of the hammer taken along the line II—II of Fig. 1;

Fig. 3 is a front view of a modified form of my invention; and

Fig. 4 is a sectional view of the modified form of hammer, taken along the line IV—IV of Fig. 3.

Referring now to the drawing for a better understanding of my invention, and more particularly to Fig. 1, I show a housing 6 formed in two halves 7 and 8 which are secured to each other by means of screws 9. The housing is formed with a bearing 11 adapted to receive a plunger 12 for reciprocation therein, and it will be observed that the plunger has been designed to weigh as little as possible and still accomplish its work.

The plunger is provided at its forward end with a head portion 13 and, at its other end, with a circular flange 15 which is disposed in a spring chamber 14 formed in the housing. The outer end of the spring chamber is threaded at 16 to receive a spring seat member 17 which is formed with a rib 18 to adjust the position of same with respect to the stop shoulder 19 provided at the forward end of the spring chamber. A compression spring 21 is interposed between the member 17 and the circular flange 15 and normally serves to hold the plunger in its forward position with the flange 15 in engagement with the stop shoulder.

In the lower portion of the housing I provide a

cam chamber 22 which merges into the spring chamber adjacent the front face of the circular flange 15. Bearings 23 and 24 are provided at the sides of the cam chamber to receive a cam shaft 26 which carries a cam 27 for engagement with the front face of the circular flange to move the plunger rearwardly against the action of the compression spring. The cam shaft is connected by means of a flexible cable 28 to the source of power, and is constantly driven in a counterclockwise direction when in use. The forward end of the housing is bored at 29 to form a sleeve 31 for the head of the plunger.

Referring now to Figs. 3 and 4 in the drawing, I show a modified form of my invention in which 15 the plunger 12 is moved rearwardly by means of a pair of cams 36 and 37 which rotate in opposite directions and engage the circular flange 15 on two sides to eliminate a side thrust on the plunger. The cam shafts 38 and 39 are journaled in 20 the housing 41 and provided with meshing gears 42 and 43 respectively. This form of my invention is suited for use on heavier gage sheet metal than the form shown in Figs. 1 and 2 and the compression spring 44 is adapted to offer a greater resistance to the action of the cams as it is formed of larger diameter wire.

While I have shown my invention in but two forms, it is obvious to those skilled in the art that it is not so limited, but is susceptible of various 30 changes and modifications without departing from the spirit thereof; and I desire, therefore, that only such limitations shall be placed thereupon as are imposed by the prior art.

I claim:

1. In a hammer, a housing, a plunger mounted for axial movement in said housing, a head formed on the forward end of said plunger, a circular flange formed on the other end of the plunger, a spring chamber formed in the housing in back of the plunger, a stop shoulder provided at the forward end of the spring chamber for engagement with the circular flange, a compression spring provided in the spring chamber and engaging the circular flange to yieldably resist a rearward movement of the plunger, a cam chamber merging into the spring chamber in front of the circular flange, a cam rotatably mounted in said cam chamber for engagement with the front face of the circular flange to move the plunger rearwardly, a spring seat member provided in the spring chamber, and means for adjusting the position of the spring seat member with respect to the stop shoulder to vary the action of the compression spring.

2. In a hammer, a housing, a plunger mounted for axial movement in said housing, a head formed on the forward end of the plunger, a circular flange provided on the other end of the plunger, a spring chamber formed in the housing in back of the plunger, a stop shoulder provided at the forward end of the spring chamber for engagement with the circular flange, a compression

spring provided in the spring chamber and engaging the circular flange to yieldably resist a rearward movement of the plunger, and a pair of cams provided for engagement with the front face of the circular flange to move the plunger rearwardly, 5

CHARLES L. GRIFFIN.
